UNITED STATES PATENT OFFICE.

JOSEPH H. SOMERVILLE, OF MENOMINEE, MICHIGAN.

DESIGN FOR A GAME-BOARD.

SPECIFICATION forming part of Design No. 25,651, dated June 16, 1896.

Application filed August 1, 1895. Serial No. 557,906. Term of patent 14 years.

To all whom it may concern:

Be it known that I, JOSEPH H. SOMERVILLE, a citizen of the United States, residing at Menominee, in the county of Menominee and 5 State of Michigan, have invented a certain new and original Design for Game-Boards; and I do declare the following to be a full, clear, and exact description of the invention, such as will enable others skilled in the art 10 to which it appertains to make and use the same.

My invention relates to a new design for a game-board, and the leading feature consists in a rectangular box, having upon its upper 15 face a number of parallel rows of perforations or depressions arranged along two opposite sides and a series of parallel rows of perforations or depressions at two diagonal corners, forming two diagonally opposite L-shaped 20 figures, which will give a very ornamental appearance to the board.

In the accompanying drawing the figure

represents a perspective view of a game-board embodying my design.

In the said drawing there is represented a 25 rectangular box, having at two opposite sides a number of parallel rows of perforations or depressions and at two diagonal ends a series of inwardly-extending parallel rows of perforations or depressions, so arranged that said 30 side and end perforations form two opposite L-shaped figures, as shown.

What I claim is—

The design for a game-board, consisting of a rectangular box having upon its upper surface side and end rows of perforations or depressions forming opposite L-shaped figures, 35 substantially as shown and described.

In testimony whereof I affix my signature in presence of two witnesses.

JOSEPH H. SOMERVILLE.
